CIRCUIT BREAKER

Harry J. Lingal, Wilkinsburg, Pa., assignor to
 Westinghouse Electric & Manufacturing Company, East Pittsburgh, Pa., a corporation of Pennsylvania

Application August 28, 1940, Serial No. 354,535

13 Claims. (Cl. 200—109)

The invention relates to circuit breakers and more particularly to the operating means and latching means therefor.

Circuit breakers of the type embodying a releasable operating member adapted to be restrained by a latch to maintain the breaker closed, or in operative condition for closing, usually employ a latch checking switch operated by the latch to insure that the circuit breaker operating mechanism is in operative latched condition ready for closing before the closing means can be energized. The latch checking switch is also sometimes used to control the operation of a counting element of the reclosing relay. Considerable difficulty has been experienced in applying latch checking switches to circuit breaker operating mechanisms due to rebounding of the latches when they are returned from the released to the latching position. This rebounding causes the latch checking switch to falsely open thereby falsely operating the counting device of the reclosing relay. As a result the reclosing relay may cause a lesser number of automatic reclosing operations than the number for which it is set.

In the case of a "single shot" recloser, i. e. one which is set to produce only a single automatic reclosing operation following tripping of the breaker, the extra openings of the latch checking switch caused by the rebound of the latch, delays automatic reclosing of the breaker longer than is desired.

An object of the invention is the provision of a circuit breaker having a releasable operating mechanism normally held in operative position by a latch, with a means for preventing rebound of the latch when it moves to latching position.

Another object of the invention is the provision of a circuit breaker mechanism having a releasable latch biased to latching position and a latch checking control switch operated by the latch, with means for preventing rebound of the latch to prevent false operation of the latch checking switch.

In accordance with the invention a metal weight, of a mass approximately equal to the mass of the latch and the parts which move with the latch, is loosely or slidably attached to either the latch or one of the parts which move with the latch. The weight is arranged so that when the latch starts to rebound toward the released position the weight is still moving toward the latched position and due to its momentum and mass overcomes and prevents the rebound motion of the latch.

The invention, both as to structure and operation, together with additional objects and advantages thereof will be best understood from the following detailed description of one embodiment thereof when read in conjunction with the accompanying drawings, in which:

Fig. 1 is a side elevational view of a circuit breaker mechanism constructed in accordance with the invention, the position of the parts being shown an instant after the circuit breaker mechanism has been tripped, and the breaker being shown schematically.

Fig. 2 is a plan view of the circuit breaker operating mechanism, the parts being shown in the closed latched position,

Fig. 3 is an end elevational view of the circuit breaker operating mechanism the parts being shown in the closed latched position.

Fig. 4 is an enlarged fragmentary view, partly in section, showing the latching mechanism moving to the latching position an instant after the releasable member has been automatically retrieved to its normal position, and

Fig. 5 is a fragmentary view similar to Fig. 4 showing the latching mechanism in the latched position and the releasable lever in the retrieved position.

Referring to the drawings, the circuit breaker comprises in general circuit interrupting means 5 which may be of conventional construction, and an operating mechanism therefor indicated generally at 7. The circuit interrupting means 5 is indicated schematically as comprising stationary contacts 9 and a cooperating movable bridging contact 11 connected by a suitable linkage system shown schematically at 13 to the operating rod 15 of the circuit breaker operating mechanism 7.

The circuit breaker operating mechanism 7, with the exception of its latching means, is generally similar to the mechanism disclosed in Patent 2,144,502 to J. B. MacNeill et al., issued January 17, 1939, and also to the mechanism shown in the copending application of Lloyd W. Dyer, et al., Serial No. 294,048, filed September 9, 1939; both of which are assigned to the assignee of the present invention. The operating mechanism 7 comprises, in general, a fabricated metal frame 17, on which is mounted a closing solenoid 19, a trip-free lever mechanism indicated generally at 21 which normally serves to connect the movable circuit breaker contact 11 to the closing solenoid 19, a latching mechanism 23 for normally holding the trip free lever mechanism in operative or thrust-transmitting condition, and an electromagnetic trip device 25 operable to move the

latching mechanism to released position to cause opening of the breaker.

The closing solenoid 19 comprises a stationary core 27, a movable core 29, and an operating winding 31 which when energized pulls the movable core downwardly to effect a closing operation of the breaker.

The trip-free lever mechanism comprises a closing lever 33 consisting of a pair of spaced parallel rigidly connected levers 35 pivoted at one end to the frame 17 by means of pivots 37, and a breaker lever 39, consisting of a pair of parallel rigidly connected levers 41 which are pivoted at one end by a pivot pin 43 to the closing lever 33 adjacent the free end thereof and disposed in the space between the levers 35 which comprise the closing lever.

The closing lever 33 is connected intermediate its ends by links 45 to the movable core 29 of the closing solenoid 19, and the breaker lever 39 is pivotally connected intermediate its ends by a pivot pin 47 to the breaker operating rod 15. The breaker lever 39 carries at its free end a trip-free roller 49 which extends transversely between the free ends of the levers 41 comprising the breaker lever, and this roller is adapted to be normally engaged and held by the latching mechanism 23 to hold the circuit breaker closed and also to hold the circuit breaker mechanism in operative condition for closing when the mechanism is automatically reset following a tripping operation.

The movable contact 11 of the circuit breaker is biased to open circuit position by means of a relatively strong spring (not shown) so that when the breaker lever 39 is released by the latching mechanism, the circuit breaker will be quickly moved to open circuit position. The closing lever 33 is biased in a counterclockwise direction about its pivot axis 37 by a pair of retrieving springs 51 positioned between the levers 35 and the frame 17. These springs serve to move the closing lever to open position when the closing lever is released during a tripping operation to cause clockwise movement of the breaker lever 39 about the pivot 47 as a fulcrum to return the trip free roller 49 to the normal or latched position where it is reengaged by the latching mechanism 23. When the trip free roller 49 and the breaker lever 39 are thus reset to latched position and engaged by the latching mechanism 23, the breaker lever 39 is reconnected to the closing lever 33 for movement thereby so that the breaker will be reclosed when the closing solenoid is energized.

A latch 53 is pivotally mounted on the frame 17 by a pivot pin 55 and is biased by a spring 57 to latching position for engaging a roller 59 carried by the closing lever 33 to hold the closing lever in closed position. The latch 53 is adapted to be moved to released position by a cross bar 61 on the breaker lever 39 during the opening movement of the breaker lever 39, thereby allowing the retrieving springs 51 to automatically reset the mechanism following each tripping operation.

When the circuit breaker is held latched in the closed circuit position, the trip free roller 49 is held down by the latching mechanism 23 in a position of alignment with the pivot axis 37 of the closing lever 33, and the closing lever 33 is also held latched down in the closed position by the holding latch 53. In this closed position, the levers 33 and 39 are in alignment with each other. When the trip device 25, which is pref-

erably a shunt trip, is energized either by the operation of suitable fault responsive relays, or by the closing of a manually controlled shunt trip circuit, the latching mechanism is thereby caused to move to the released position effecting release of the trip free roller 49 and the breaker lever 39. The movable contact 11 of the circuit breaker being no longer held in closed position is quickly moved to open circuit position by its biasing spring and in doing so moves the breaker lever 39 in a clockwise direction about its pivot 43 to the open position shown in Fig. 1. During the movement of the breaker lever 39 to open position, the cross bar 61 thereof engages and moves the holding latch 53 to the released position effecting release of the free end of the closing lever 33. The retrieving springs 51 then move the closing lever counterclockwise about its fixed pivot axis 37 to open position indicated by the dotted lines in Fig. 1. This opening movement of the closing lever 33 moves the breaker lever 39 in a counterclockwise direction about the pivot pin 47 as a fulcrum to return the trip free roller 49 to the latched position where it is reengaged by the latching mechanism 23. Both levers 33 and 39 now occupy the position indicated by the dotted lines in Fig. 1 and the mechanism is reset and ready to be reclosed. When the solenoid 19 is energized to reclose the breaker, the two levers 33 and 39 are rotated together in a clockwise direction about the pivot axis 37, to closed position, and the roller 59 of the closing lever is reengaged and latched by the holding latch 53 to hold the closing lever in closed position.

The latching mechanism 23 comprises a latch 63 pivotally mounted on the frame 17 by a pivot pin 65 and having a latch projection 67 for engaging the trip free roller 49 of the breaker lever 39 to hold the roller 49 and the lever 39 in latched position. The latch 63 also comprises a pin 69 adjacent the free end which pivotally supports one member 71 of a toggle; the other member 73 of the toggle being pivotally mounted on the frame 17 by means of a rotatable shaft 75 to which the member 73 is rigidly clamped at its lower end by screws 77. The shaft 75 is rotatably mounted in bearings 79 provided therefor on the frame 17, and one end of the shaft 50 extends laterally beyond the side of the frame 17 as shown in Figs. 2 and 3. The adjacent ends of the toggle members 71 and 73 are pivotally connected together by a knee pivot pin 81.

A tension spring 83 is connected at one end to the toggle member 73 adjacent the knee of the toggle and this spring serves to bias the latch 63 to latching position and the toggle to the extended or "in toggle" position to thereby maintain the latch in latching position. The inward movement of the latch 63 and latch toggle 71-73 is limited by cooperating stop surfaces 85 and 87 formed on the adjacent ends of the toggle members 71 and 73.

In the latching position of the latch 63, the toggle 71-73 is approximately in dead center position, i. e., the knee pivot pin 81 is located approximately on a line joining the axis of the pivot shaft 75 and the axis of the pivot pin 69. In the embodiment shown, the center of the knee pivot pin 81 is located a small distance to the right of this center line so that the toggle 71-73 is very slightly overset. It is to be understood, however, that the toggle may be disposed exactly on dead center or slightly under set if desired and reli-

ance placed on the spring 83 to maintain the latch in latching position.

The toggle member 73 is provided with a projection 89 adjacent its fixed pivot end which is disposed over the trip plunger of the trip device 25 so as to be engaged and moved by the trip plunger to effect tripping of the breaker when the trip device is actuated. The projection 89 carries an adjustable spring bumper 91 which is adapted to engage the frame 17 when the latch is moved to latching position to absorb some of the kinetic energy of the moving latch parts. The spring bumper also assists in initiating movement of the latch parts to released position upon operation of the trip device 25.

The trip device 25 comprises a solenoid having a stationary core 93, a movable core 95, and an energizing winding 97. A trip plunger rod 99 is carried by the movable core 95 and extends up through aligned openings in the stationary core 93 and the frame 17. When the winding 97 is energized, the trip plunger 99 is moved upwardly by the core 95 and engages and moves the toggle member 73 in a counterclockwise direction causing collapse of the toggle and movement of the latch 63 toward released position thereby effecting release of the trip free roller 49 and breaker lever 39.

A toggle locking lever 86 is provided for the purpose of preventing the latch 63 from returning to latching position following release until after the trip free roller 49 has been automatically retrieved or reset to its normal position. This prevents the latch checking switch, herein-after described, which is controlled by the latch from being operated more than one time for each opening operation of the breaker. The toggle locking lever 86 is pivotally mounted on the pivot pin 65 at the side of the latch 63 and is biased in a clockwise direction, as viewed in Fig. 1, by the spring 83 which is anchored at one end to a tailpiece of the toggle locking lever 86. A projection 88 of the toggle locking lever is disposed to be engaged by the end of the breaker lever 39 which carries the trip free roller 49, so as to hold the toggle locking lever down in an inoperative position whenever the trip free roller 49 is in its normal or latched position. The toggle locking lever 86 is provided with another projection 90 which is adapted to be moved into blocking relation in the path of the knee pivot pin 81 of the toggle 71-73 whenever the trip free roller 49 is away from its normal position thereby preventing movement of the toggle 71-73 and latch 63 to latching position until the trip free roller 49 is retrieved to normal position. The toggle locking lever 86 is shown in locking position in Fig. 1. When the trip free roller 49 is automatically retrieved to its normal position as shown in Fig. 4, the end of the breaker lever 39 engages the projection 88 of the toggle locking lever 86 and depresses the toggle locking lever thereby causing the projection 90 thereof to be moved out of the path of the knee pivot pin 81 of the toggle to permit the toggle and latch 63 to be moved to latching position by the spring 83. Fig. 5 shows the position of the parts after the latch 63 has been moved to latching position in engagement with the trip free roller 49. In this position, the circuit breaker mechanism is fully reset and ready to be reclosed.

A latch checking switch 103 is mounted on the frame 17 at the side of the latching mechanism 23 and this switch is adapted to be operated in response to the movement of the latch 63 to

check the position of the latch. The switch 103 is biased to open circuit position by a spring (not shown) and is adapted to be closed by depressing a pushbutton 105 which projects through the top 5 of the switch casing. The switch 103 is held closed only as long as the pushbutton 105 is held in depressed position. The latch checking switch 103 is adapted to be operated in accordance with the movement of the latch 63 by means of an 10 arm 107 which is secured to the shaft 75 of the toggle member 73. When the latch 63 and toggle 71-73 move to latching position, the arm 107 depresses the pushbutton 105 closing the latch checking switch 103, and the switch remains 15 closed as long as the latch 63 remains in latching position.

The latch checking switch is usually connected in series with the operating coil of the reclosing relay and with an auxiliary switch of the breaker which is arranged to close when the breaker reaches open position as disclosed in the copending application of Lloyd W. Dyer, et al., Serial No. 294,048, previously referred to. In such instance, the closing solenoid cannot be energized 20 to reclose the breaker until the operating mechanism has been automatically reset and the latch 63 is in latching engagement with the trip free roller 49. It has been found, however, that due to the high speed operation of the parts, the 25 latch 63 rebounds several times when it moves to latching position in engagement with the trip free roller 49. These rebounds of the latch 63 cause 30 undesired opening operations of the latch checking switch 103 and as a result the operating coil of the reclosing relay does not effect sufficient 35 energization of the closing solenoid 19 to initiate automatic reclosing of the breaker until after the latch 63 stops rebounding and remains in latched position. This delay is longer than is desired 40 particularly where high speed automatic reclosing is required. In other types of automatic reclosing circuit breaker systems, the latch checking switch in addition to controlling the reclosing relay also operates the counting element of the 45 reclosing relay, and in such instance if the latch rebounds, the latch checking switch opens thereby causing the counting element of the reclosing relay to falsely operate. Consequently, a reclosing relay set to cause a definite predetermined 50 number of automatic reclosing operations of the breaker, would actually cause a lesser number of reclosures because of faulty counting of the reclosing relay which was due to the rebound of the circuit breaker operating mechanism latch. 55 In Figure 5 of the drawings I have illustrated a bound of the latch 63 and the consequent false operation of the latch checking switch 103 is prevented by a weight which is loosely mounted to move with the latch and has a mass approximately equal to the effective free weight and 60 mass of the latch and the parts which move with the latch. In the embodiment of the invention illustrated, a metal weight 109 is loosely disposed in a recess or pocket 111 provided therefor in the toggle member 73. The metal weight 109 is freely movable a limited amount in the pocket 111 relative to the toggle member 73 in the direction of movement of the member 73, and the weight is retained in the pocket by a cover plate 65 113 which is secured to the toggle member 73 over the open side of the recess or pocket 111 by a plurality of screws 115.

The weight 109, as determined by experiment, should preferably have a weight and mass approximately equal to the effective free weight

and mass of the movable latch parts comprising the latch 63 and its toggle 71-73. The weight should preferably be carried by the moving latch part having the longest travel and moving at the highest speed. Moreover, it is desirable that the weight should be mounted so as to move as nearly as possible in a horizontal path to reduce the effects of gravity and so as not to materially affect the normal operating speed of the latch parts.

When the latch 63 is moved toward latching position by the spring 83, after retrieving of the trip free roller 49, the weight 109 at this instant is in its outermost position against the cover plate 113 as shown in Fig. 4, but is still moving in a direction toward the latch 63. By the time the latch 63 and toggle member 73 start to rebound from latching position, the weight 109 which is still moving inwardly toward the latch strikes the toggle member 73 and overcomes the rebound movement due to the momentum and mass of the weight. The rebound of the latch 63 and toggle member 73 is thus prevented or reduced to such a very slight amount that the latch checking switch 103 will not be opened thereby.

While the invention has been disclosed in accordance with the patent statutes, it is to be understood that various changes may be made in construction disclosed without departing from some of the essential features of the invention.

I claim as my invention:

1. In a circuit breaker having an operating member releasable to cause opening of the breaker, a movable latch for engaging and holding said operating member in operative position, said latch being biased to latching position, trip means operable to move said latch to released position to effect release of said operating member, an auxiliary switch controlled by said latch, and means operable to prevent rebound of said latch toward released position to thereby prevent false operation of said auxiliary switch, said last mentioned means normally permitting movement of said latch toward released position.

2. In a circuit breaker having a member releasable to cause opening of the breaker, a movable holding means for restraining said member in operative position, spring means biasing said holding means to holding position, trip means operable to move said holding means to released position to release said member, an auxiliary switch operated by said holding means, means automatically effective to prevent return of said holding means to holding position until said releasable member is returned to its operative position, and means operable to prevent rebound of said holding means toward released position when said holding means is moved to holding position, said rebound preventing means permitting movement of said holding means to released position at all other times.

3. In a circuit breaker having a member releasable to cause opening of the breaker, a movable holding means for restraining said member in operative position, spring means biasing said holding means to holding position, trip means operable to move said holding means to released position, an auxiliary switch controlled by said holding means and means operable by the movement of said holding means to holding position for opposing rebound of said holding means toward released position to thereby prevent false operation of said auxiliary switch.

4. In a circuit breaker having a member re-

leasable to cause opening of the breaker, a movable latch for engaging and restraining said member in operative position, spring means biasing said latch to latching position, trip means

5 operable to move said latch to released position, an auxiliary means controlled by said latch, means automatically effective to prevent return of said latch to latching position until said releasable member is returned to operative position 10, and means movable with said latch operable to oppose rebound of said latch toward released position to thereby prevent false operation of said auxiliary means.

5. In a circuit breaker having a member re- 15 leasable to cause opening of the breaker, a movable latch for engaging and restraining said member in operative position, spring means biasing said latch to latching position, trip means operable to move said latch to released position, 20 an auxiliary switch controlled by said latch, and means comprising a weight of predetermined mass movable by said latch and operable to oppose rebound of said latch to thereby prevent false operation of said auxiliary switch.

25 6. In a circuit breaker having a member re- leasable to cause opening of the breaker, a movable latch for engaging and restraining said member in operative position, a toggle connected to said latch, spring means connected to said 30 toggle for biasing said latch to latching position, trip means operable to effect movement of said latch to released position to release said member, and means comprising a weight of predetermined mass movable with said latch and operable 35 to prevent rebound of said latch toward released position when said latch is moved to latching position.

7. In a circuit breaker having a member re- 40 leasable to cause opening of the breaker, a movable latch for engaging and restraining said member in operative position, a toggle connected to said latch, spring means connected to said toggle for biasing said latch to latching position, trip means operable to effect movement of said 45 latch to released position to release said member, and means comprising a weight of predetermined mass carried by said latch toggle operable to prevent rebound of said latch toward released position when said latch is moved to latching 50 position.

8. In a circuit breaker having a member re- 55 leasable to cause opening of the breaker, a movable latch for engaging and restraining said member in operative position, a toggle connected to said latch, spring means connected to said toggle for biasing said latch to latching position, trip means operable to effect movement of said latch to released position to release said member, and means comprising a weight of predetermined 60 mass movable with said latch and operable to prevent rebound of said latch toward released position when said latch is moved to latching position, said weight being mounted on said toggle for limited movement relative thereto in the direction of movement of said toggle and having a mass approximately equal to the effective mass of said latch and toggle.

9. In a circuit breaker having an operating mechanism including a member releasable to 70 cause opening of the breaker, a movable holding means for restraining said member in operative position, spring means for biasing said holding means to holding position, trip means operable to cause movement of said holding means to released position to release said member, an

auxiliary control switch operated by the movement of said holding means, and means comprising a weight of predetermined mass movable with said holding means operable to prevent rebound of said holding means to thereby prevent false operation of said auxiliary control switch.

10. In a circuit breaker having an operating mechanism including a member releasable to cause opening of the breaker, a movable latch for restraining said member in latched position, spring means for biasing said latch to latching position, trip means operable to cause movement of said latch to released position to release said member, an auxiliary control switch operated by the movement of said latch, and means comprising a weight of predetermined mass movable with said latch operable to prevent rebound of said latch to thereby prevent false operation of said auxiliary control switch, said weight being movable a limited amount relative to said latch approximately in the direction of movement thereof.

11. In a circuit breaker having an operating mechanism including a member releasable to cause opening of the breaker, means comprising a toggle for restraining said member in an operative position, a spring for biasing said toggle to restraining position, trip means operable to cause collapse of said toggle to release said member, an auxiliary control switch operated by the movement of said toggle, and means operative to prevent rebound of said toggle to thereby prevent false operation of said auxiliary control switch.

12. In a circuit breaker having an operating mechanism including a member releasable to cause opening of the breaker, a pivoted latch for restraining said member in latched position, a toggle connected at one end to said latch, spring means connected to said toggle for biasing said latch to latching position, trip means operable to cause movement of said latch to released position to release said member, said member being resettable to latched position following its release, an auxiliary control switch operated by the movement of said latch, and means comprising a weight of predetermined mass movable with said latch operable to prevent rebound of said latch to thereby prevent false operation of said auxiliary control switch.

13. In a circuit breaker having an operating mechanism including a member releasable to cause opening of the breaker, a pivoted latch for restraining said member in latched position, a toggle connected at one end to said latch, spring means connected to said toggle for biasing said latch to latching position, trip means operable to cause movement of said latch to released position to release said member, said member being resettable to latched position following its release, an auxiliary control switch operated by the movement of said latch, and means comprising a weight of predetermined mass carried by said toggle and movable a limited amount relative thereto in the direction of movement of said toggle for preventing rebound of said latch to thereby prevent false operation of said auxiliary control switch.
